[57] **CLAIM**

The ornamental design for a sunglasses temple, as shown and described.

DESCRIPTION

FIG. 1 is a front perspective view of a sunglasses temple showing my new design; the broken line showing of the rest of the spectacles is for illustrative purposes only and forms no part of the claimed design;

FIG. 2 is a front elevation view thereof;

FIG. 3 is a top plan view thereof;

FIG. 4 is an inverted rear elevational view thereof;

FIG. 5 is a left end elevational view thereof; and,

FIG. 6 is a right end elevational view thereof.
